JOHN H. CARR, OF EVERETT, MASSACHUSETTS.

PLUMBER'S TRAP.

1,152,077.

Specification of Letters Patent.

Patented Aug. 31, 1915.

Application filed January 29, 1914. Serial No. 815,191.

To all whom it may concern:

Be it known that I, JOHN H. CARR, a citizen of the United States, and resident of Everett, in the county of Middlesex and 5 State of Massachusetts, have invented certain new and useful Improvements in Plumbers' Traps, of which the following is a specification.

This invention relates to plumbers' traps 10 and consists in certain improved features of construction and assemblage hereinafter described in detail.

One of the objects of the invention is to provide improved means for joining a lead 15 casing and a screw-threaded ring by which the trap cover is attached.

Another object of the invention is to provide connection, other than the casing, between the aforesaid ring and the discharge 20 pipe, whereby the pipe and ring may brace each other. For the latter purpose the pipe and ring may be either integral or separate; but when they are separate they are formed with interlocking portions whereby they 25 are adapted to have the bracing effects referred to.

Another object of the invention is to provide a lead trap whose cap joint will be sealed by the liquid in the trap and which 30 will not overflow when the cap is removed.

These and other objects will be better understood after the structure has been described in detail.

Of the accompanying drawings: Figure 1 35 represents a vertical section through a trap embodying one form of my invention. Fig. 2 represents a cross section of the same in the plane indicated by line $x-x$ of Figs. 1 and 3. Fig. 3 represents a view, similar to 40 Fig. 1, of a trap embodying one feature of my invention in another form. Fig. 4 represents a cross section of the trap shown by Fig. 3 in the plane of line $x-x$.

The same reference characters indicate the 45 same parts wherever they occur.

The trap, as shown, comprises a cup-shaped casing 10 of relatively soft ductile metal, such as lead, a cap 11, a ring 12 for holding said cap, and an outlet pipe 13 the 50 receiving end of which projects into the casing. The cap and ring have coöperative connecting screw-threads indicated at 14. The receiving end 15 of the outlet pipe is arranged at a substantial distance below the 55 rim 16 of the casing in order to prevent overflow of the casing when the cap is re-

moved. The ring 12 is disposed at a substantial distance below the receiving end 15 of the outlet pipe so that the screw-threaded joint 14 will be sealed by liquid when the 60 trap is in use.

One improvement of the trap consists in the means whereby the ring 12 is secured in the casing. The ring for this purpose is formed with a continuous peripheral groove 65 17 and the wall of the casing is offset or depressed, as indicated at 18, into the groove, the offset portion affording a firm support for the ring. To guard against any possibility of leakage between the casing and 70 ring, I apply a ring of solder, as indicated at 19. The element indicated at 20 is a gasket for the purpose of forming a tight joint between the cap and ring.

So far as I am aware, this is the first instance of a lead trap having an integral portion extending above the joint by which 75 the cap is attached, and this feature is due in the present instance to the offsetting of the casing at 18 to form a flange in the peripheral groove of the ring. The offset 80 portion of the casing may be formed readily by spinning.

The outlet pipe 13 has an elbow turn at 85 21 whereby the discharge end of the pipe is caused to extend to the side wall of the casing. I form the joint at the discharge end by cutting a hole in the side wall of the casing, and by then depressing the rim of the hole inwardly, by spinning or otherwise, 90 to form a flange 22 adapted to coöperate with the outlet pipe to form an annular groove for the reception of solder 23 by which the joint is made tight. The depressing of the casing at this point facilitates the 95 application of the solder 23, because when the trap is laid on its side with the joint uppermost the solder may be readily poured into the annular groove provided for its reception. I prefer to arrange the discharge 100 end of the pipe substantially flush with the periphery of the casing and to form the ring of solder 23 so that it will also be flush with the periphery of the casing. By thus avoiding projection of the outlet pipe 105 beyond the casing, the joint is less likely to develop a leak in consequence of handling. During transportation of the traps the boxes in which they are packed are often dropped, and thus traps whose outlet pipes 110 project beyond the casing often receive blows on the projecting pipes which cause

the joints to leak, and the traps in being handled separately are oftentimes subjected to blows which result in destruction of the joints. These causes of injury are avoided to a great extent by arranging the outlet pipe so that its discharge end does not project beyond the casing.

I have shown the casing as being provided with an inlet hole at 24. This hole will, in practice, be made after the trap has been installed, and its location will be determined by the direction from which the inlet pipe is led.

Careless persons sometimes apply too much force when attaching the cap 11, the cap being provided with suitable means whereby a wrench or other tool may be used to turn it; and in this instance it is provided with lugs 25 between which a flat tool 29 may be inserted to operate as a wrench. The joint between the lead casing and ring 12, although otherwise strong enough, may not be sufficient to withstand excessive wrenching strains applied to the cap, and for this 25 reason I provide means for bracing the ring against rotative movement relatively to the casing so that there will be no likelihood of starting a leak between the ring and casing. In the form shown by Figs. 1 and 2, the 30 means for this purpose is embodied in co-operative abutments on the outlet pipe and ring respectively. The ring as shown is provided with a horizontal web or flange 26 in which is formed a radial notch 27; and 35 the outlet pipe is provided with a lug 28 which projects radially so as to occupy the notch 27. Whatever rotative strain is imparted by the cap to the ring is transmitted by the web 26 to the lug 28 and thence to the 40 outlet pipe. Since the discharge end of the outlet pipe is secured to the casing by a strong joint, it is adapted to brace the ring 12 so as to prevent rotative movement of the ring. The solder 19 is thus relieved of 45 rotative strains, and the joint formed thereby will remain tight. In some cases I may form the ring 12 and outlet pipe 13 integrally by a single casting, as shown by Fig. 3, the two parts in this figure being joined 50 by a web 26'. This web does not wholly surround the outlet pipe, because it is necessary for the liquid to flow upwardly outside the pipe 13 in order to pass from the inlet 24 to the receiving end 15 of the outlet pipe. 55 It does, however, surround the outlet pipe sufficiently to afford the necessary strength and also to prevent complete discharge of the liquid from the trap by siphonic action.

The flange 26 is adapted to hold the pipe 60 13 in place while the solder 23 is being applied, and during this soldering operation the pipe in Fig. 1 may be securely held against the flange by inserting a wedge or other suitable piece (not shown) between 65 the ring 12 and the pipe, diametrically

opposite the lug 28. The discharge pipe, in this form, need not be placed in the casing until after the ring 12 has been secured by depressing the casing into the groove 17, and the pipe may be introduced through the 70 hole defined by the flange 22. The discharge pipe may, however, be joined to the casing at 22, 23 before the ring 12 is joined to the casing. In such case, the pipe, having been made fast to the casing, may be utilized to 75 hold the ring in place during the operation of spinning or otherwise depressing the casing into the groove of the ring as indicated at 18. In the latter case the wedge or other suitable piece hereinbefore mentioned would 80 be driven between the pipe and ring at a point diametrically opposite the lug 28. In the form shown by Fig. 3 the pipe and ring would enter through the top of the casing. A flange 30 on the pipe is arranged to engage the flange 22 to position the pipe.

The waste pipe may be installed before the trap is installed, in which case the discharge end of pipe 13 would be screwed upon the waste pipe by turning the entire trap. 90 If, however, the trap be installed before the waste pipe is installed, the latter would be screwed into the pipe 13. In either case the relative turning of the two pipes would involve a torsional stress upon the discharge 95 end of pipe 13. Such stress would necessarily be great in order to make the screw-threads tight enough to prevent leaking, and would tend to loosen the solder joint at 23 unless some means were provided for bracing pipe 13 against turning relatively to the casing 10. Such means is present in both modifications, the connection between the upturned portion of pipe 13 and the ring 12 being effective for bracing the pipe so as to 100 sustain the torsional stress referred to. This relieves the solder joint at 23 from sustaining such stress, and eliminates the likelihood of loosening the said joint.

When the trap is in use, the pipe 13 is 110 never subjected to any strain other than that hereinbefore mentioned of wrenching the cap with too much force; and since the discharge end of the pipe is secured in the side wall of the casing as distinguished from the 115 bottom, the pipe is enabled to perform its bracing function without liability of injuring the joint at its discharge end. This strain is sustained directly by the flange 22 as well as by the solder 23.

I claim:

1. A trap comprising a casing, an outlet pipe joined with the side wall of said casing, said pipe having an elbow portion within the casing and extending toward the top of the casing, and means arranged to coact with the side wall of the casing and with said elbow portion to sustain stresses which would tend to loosen the joint of said pipe and casing.

2. A trap comprising a casing composed of soft ductile metal and having a rim at its upper end, a cap for said casing, a cap-receiving ring arranged within said casing 5 and a substantial distance below said rim, said ring having a circumferential groove and said casing having an internal annular offset portion occupying said groove, said ring and cap having coöperative connecting screw-threads, and an outlet pipe joined with said casing below said ring and projecting into said casing and ring, the receiving end of said pipe being above the screw-threads of said ring, and the rim of said 15 casing being above the receiving end of said pipe.
3. A trap comprising a casing, a ring arranged in and joined to said casing, an outlet pipe projecting into said casing and into 20 said ring, said pipe being joined with the wall of said casing, and a web extending from said ring to said pipe to brace the latter.
4. A trap comprising a casing, a ring arranged in and joined to said casing, a cap, 25 said ring and cap having coöperative connecting screw-threads, an outlet pipe joined with the wall of said casing and projecting into said casing, and means connecting said ring and pipe to cause the latter to sustain rotative stresses transmitted by said cap to said ring.
5. A trap comprising a casing, a ring arranged in and joined to said casing, a cap, 30 said ring and cap having coöperative con-

necting screw-threads, an outlet pipe joined with the side wall of said casing and projecting into said casing, the receiving end portion of said pipe being within said ring, the axis of the joined portion of said pipe 40 being substantially radial with relation to the axis of said ring, and means connecting said ring and pipe to cause the latter to sustain rotative stresses transmitted by said cap to said ring.

6. A trap comprising a casing, an outlet pipe joined with the side wall of the casing, said pipe having a portion extending into said casing and upwardly therein, a ring within said casing and joined to the side 50 wall thereof, said ring being arranged to surround said portion and having a cap-receiving screw-thread, and means arranged to transmit rotative stress from said ring to said pipe to brace said ring against movement relatively to said casing.

7. A trap comprising a casing, an outlet pipe a portion of which is joined to the wall of said casing, another portion of said pipe projecting into the casing, and means in said 60 casing and coacting with the latter and with said other portion to sustain torsional stress applied to said joined portion of said pipe.

In testimony whereof I have affixed my signature, in presence of two witnesses.

JOHN H. CARR.
